CLAIM

(22) Filed: **Aug. 29, 2000**

The ornamental design for a flush actuator for sanitary systems, as shown and described.

(30) **Foreign Application Priority Data**

DESCRIPTION

Mar. 15, 2000 (XH) DMA/004 818

FIG. 1 is a perspective view of a flush actuator for sanitary systems in accordance with the present design.

(51) LOC (7) Cl. **23-02**

FIG. 2 is a left-side elevation view thereof;

(52) U.S. Cl. **D23/309**

FIG. 3 is a top plan view thereof;

(58) **Field of Search** D23/250, 252,

FIG. 4 is a rear elevation view thereof;

D23/254, 301, 309, 313; D8/300, 306-307;

FIG. 5 is a front elevation view thereof;

4/300, 328, 329, 353-354, 419, 405-407,

FIG. 6 is a right-side elevation view thereof; and,

384

FIG. 7 is a bottom plan view thereof.

The broken lines shown in FIGS. 1, 4, 5, 6 and 7 are for illustrative purposes only and form no part of the claimed design.
